[57] CLAIM

The ornamental design for a fastener disk, as shown and described.

DESCRIPTION

FIG. 1 is a front perspective view of a first embodiment of a fastener disk showing our new design;

FIG. 2 is a side elevational thereof, the opposite side being identical thereto;

FIG. 3 is a top plan view thereof;

FIG. 4 is a front elevational view thereof, the back elevational view being identical thereto;

FIG. 5 is a bottom plan view thereof;

FIG. 6 is a front perspective view of a second embodiment of a fastener disk showing our new design;

FIG. 7 is a side elevational view of the second embodiment, the opposite side being identical thereto;

FIG. 8 is a top plan view of the second embodiment;

FIG. 9 is a front elevational view thereof, the back elevational view being identical thereto; and,

FIG. 10 is a bottom plan view of the second embodiment. The broken lines shown in the drawings are for environmental purposes and form no part of the claimed design.
